Patented Oct. 12, 1971

222,281

BOARD FOR A DART-TYPE GAME

John J. Feagans and Leo J. Jehle, both of
9431 Theodosia, St. Louis, Mo. 63114

Filed Mar. 27, 1970, Ser. No. 22,076

Term of patent 14 years

Int. Cl. D21—01

U.S. Cl. D34—5

The figure shows a plan view of a board for playing a dart-type game.

The board is of conventional thickness.

We claim:

The ornamental design for a board for a dart-type game, substantially as shown and described.
